UNITED STATES PATENT OFFICE.

HOMER CLINTON, OF ELDORA, IOWA.

WINDMILL.

SPECIFICATION forming part of Letters Patent No. 570,123, dated October 27, 1896.

Application filed May 27, 1896. Serial No. 593,336. (No model.)

To all whom it may concern:

Be it known that I, HOMER CLINTON, a citizen of the United States, residing at Eldora, in the county of Hardin and State of Iowa, 5 have invented a new and useful Windmill, of which the following is a specification.

The invention relates to improvements in windmills.

The object of the present invention is to 10 improve the construction of windmills and to provide a simple and comparatively inexpensive one which will be positive and reliable in operation, and to enable the wind to be entirely excluded from the wind-wheel when 15 the windmill is thrown out of operation to prevent the same from being injured by high winds or heavy storms.

The invention consists in the construction and novel combination and arrangement of 20 parts hereinafter fully described, illustrated in the accompanying drawings, and pointed out in the claims hereto appended.

In the drawings, Figure 1 is a perspective view of a windmill constructed in accordance 25 with this invention, the doors being open to admit wind to the wind-wheel. Fig. 2 is a horizontal sectional view of the same. Fig. 3 is a similar view, the doors being closed. Fig. 4 is a vertical sectional view of the windmill. Fig. 5 is a detail sectional view illustrating the construction of the gearing for 30 transmitting motion from the wind-wheel to a pump-rod or the like.

Like numerals of reference designate corresponding parts in all the figures of the drawings.

1 designates a rectangular frame designed to be mounted on a tower or other suitable support and receiving a horizontal wind-wheel 40 2, which is mounted loosely on a vertical shaft 3 and which is designed to communicate motion to a pump-rod or the like. The frame 1 is composed of a top 4, a bottom 5, and corner posts or uprights 6, and it has mounted between its top and bottom an annular series of 45 posts or supports 7, to which are hinged doors 8, arranged in an annular series and admitting, when open, wind to the wind-wheel and entirely excluding wind from the wheel when 50 they are closed. Each door 8 is hinged to one post or support 7, and, when closed, its free edge abuts against the adjacent post or

support, and the entire series of doors are simultaneously opened and closed by means of a ring 9, connecting with the doors and with 55 suitable operating mechanism.

When the doors are open, they are adapted to admit the wind to the wind-wheel from any direction which receives the full power of the wind to operate it, but it is not retarded by 60 the same, as the blades 10 of the wind-wheel, when coming into the wind, are shut off from the same by the doors until they arrive at a position directly in front of the wind.

The wind-wheel, which may be of any desired construction, is preferably composed of 65 blades 10, slightly angular in cross-section in order to hold the wind, and mounted in a suitable frame, consisting of a top 11 and a bottom 12, the blades serving as the means 70 for connecting the top and bottom of the wind-wheel frame. The top and bottom of the wind-wheel frame are preferably provided with radial cleats 13 to enable the ends of the blades to be readily attached to them. The 75 vertical shaft, upon which the wind-wheel is mounted, is designed to be provided with suitable brackets or bearings, so that it will be firmly mounted in proper position.

The ring 9, which is adapted to reciprocate 80 to open and close the doors 8, is mounted in suitable guides 14, consisting of loops of horizontal rods which extend from the uprights or corner-posts 6 of the frame to the adjacent post or supports 7 of the hinged doors 8, and 85 the ring is connected with the doors by link rods 15. When the doors are open, their outer edges are supported by a ring, which is located at the exterior of the doors, and it prevents any liability of the doors opening too 90 far, as it forms a stop for them. The operating mechanism for reciprocating the ring to open and close the doors consists of a pair of chains 16, or similar flexible connections, located at opposite sides of the frame 1, attached to the ring, and passing over pulleys 95 17, which are mounted on the frame. The chains 16 depend from the frame 1 and extend to the base of the supporting-frame or tower, and they are designed to be connected 100 with suitable operating-levers. One chain is adapted to reciprocate the ring in one direction and the other chain in the opposite direction, and the doors may be quickly oper-

ated to expose the wind-wheel to the wind or to exclude the latter from the wind-wheel.

The wind-wheel is provided at its bottom with an eccentric 18, mounted on the lower 5 face of the bottom of the wind-wheel frame and consisting of three triangularly-arranged rollers mounted in a suitable support or bearing and adapted to engage a reciprocating bar 19. The reciprocating bar 19, which is 10 disposed horizontally and which is located beneath the wind-wheel, is mounted in bearings 20 and 21, and is provided at its upper face with opposite stops 22, forming a recess, located at opposite sides of the vertical wind- 15 wheel shaft and receiving the eccentric. The vertical wind-wheel shaft passes through a slot of the reciprocating bar. The bearing 22 is provided with a roller 23 to receive the reciprocating bar, and the latter is connected 20 by a link 24 with one arm of a bell-crank lever 25. The bell-crank lever 25, which is fulcrumed at its angle in a slot or opening of the bottom of the main frame 1, has its upper arm arranged in the slot of the reciprocating 25 bar, and its other arm is designed to be connected with a pump-rod or other suitable device for transmitting motion from the wind-wheel to the machine or apparatus to be operated. The eccentric may be arranged at 30 any desired distance from the shaft in order to obtain the desired speed or power.

It will be seen that the windmill is simple and comparatively inexpensive in construction, that it is positive and reliable in operation, and that the wind-wheel is adapted to receive the full force and effect of the wind and may be entirely shut off from the same.

Changes in the form, proportion, and minor details of construction may be resorted to 35 without departing from the principle or sacrificing any of the advantages of this invention.

What I claim is—

1. In a windmill, the combination of a frame,

45 a horizontal wind-wheel, an annular series of vertical posts mounted on the frame, an annular series of outwardly-opening doors hinged at one edge to the vertical posts and having their other edge free and arranged to abut against the adjacent post in closing a reciprocating horizontally-disposed ring mounted on the frame, encircling the doors and connected with the same, said ring being adapted to open and close the doors, and also forming a stop to limit their outward swing, and 50 means for operating the ring, substantially as described.

2. The combination of a frame, a horizontal wind-wheel mounted thereon, horizontally-aligned bearings mounted on the frame 60 and located beneath the wind-wheel, one of the bearings being provided with a roller, a horizontally-disposed reciprocating bar slidingly mounted in said bearings, an eccentrically-arranged roller depending from the wind-wheel and engaging the reciprocating bar, and a bell-crank lever fulcrumed at its angle on the frame and having one arm connected with the reciprocating bar at a point intermediate with the ends thereof, substantially 65 as described.

3. In a windmill, the combination of a frame provided with bearings, a horizontally-disposed reciprocating bar slidingly mounted in the bearings, a horizontal wind-wheel located 70 above the bar, the triangularly-arranged rollers depending from the wind-wheel and engaging the reciprocating bar, and a bell-crank lever fulcrumed at its angle on the frame and having one arm connected with the reciprocating bar, substantially as described.

In testimony that I claim the foregoing as my own I have hereto affixed my signature in the presence of two witnesses.

HOMER CLINTON.
